CLAIM

The ornamental design for a locking device having a cable, as shown and described.

DESCRIPTION

FIG. 1 is a front elevational view of a locking device having a cable showing my new design;

FIG. 2 is perspective view thereof;

FIG. 3 is another perspective view thereof;

FIG. 4 is a perspective view thereof, showing in an alternate position; and,

FIG. 5 is a perspective view thereof, shown in the environmental use.

The broken lines illustrate environment and forms no part of the claimed design.

The appearance of any portion of the article between the break lines form no part of the claimed design.
